UNITED STATES PATENT OFFICE.

HARMEN ERNSBERGER, OF NORTH CREEK, OHIO.

CUTTER-HEAD.

SPECIFICATION forming part of Letters Patent No. 509,301, dated November 21, 1893.

Application filed January 7, 1893. Serial No. 457,599. (No model.)

To all whom it may concern:

Be it known that I, HARMEN ERNSBERGER, a citizen of the United States of America, residing at North Creek, in the county of Putnam and State of Ohio, have invented certain new and useful Improvements in Cutter-Heads, of which the following is a specification, reference being had therein to the accompanying drawings.

My invention relates to an improved cutter-head for planing-machines, and possesses the following characteristics: The construction of the head is such that I am enabled to secure the cutters therein without forming slots or bolt-holes in it; to place more cutters in a head of a given size than has heretofore been practicable; to so secure the cutters in the head that the strain on the cutter for the time being in contact with the board to be planed is transmitted throughout the entire head, thereby avoiding all danger of the latter breaking at any of its sockets; to secure the cutters in the head in such a manner that they will be supported at their cutting-edges on both sides, whereby all possibility of the cutters springing is avoided, and also in such a manner that the cutters will make a shaving or draw cut, in contradistinction to what is known as the scraping cut; and, furthermore, by the peculiar construction of the head and cutter-fastenings I am enabled to use cutters until they have been worn away to less than one-third their original length.

In the drawings, Figure 1 is a perspective view of a cutter-head of my improved form. Fig. 2 is an end view of the same. Fig. 3 is a detail view of the fastening device, showing the parts separated.

Referring to the drawings, A is a cutter-head, having gudgeons 1 and circular cutter-sockets 2, in which latter are secured cutter-knives B, of a curvature corresponding to that of the sockets. The knives are secured in place in the sockets by fastenings C, each of which consists of clamp-blocks 3, held apart by a bolt 4, threaded at 5 and provided with a nut 6, as will be fully understood from Fig. 3. Each clamp-block has a central bolt-hole 7, into which the ends 8 of the bolt 4 project, a bolt-head 9 being formed on the bolt a short distance from one end. When the knife is put in place, the nut 6 is screwed up on the

bolt 4, the clamp-blocks are placed on the ends of the bolt, and the whole device slipped into the end of the knife-socket. One clamp-block is set to bear against the knife, and the other block to bear against the inner side of the knife-socket, after which the nut 6 is screwed so as to tighten up the clamp-blocks and hold the knife firmly against the head. 55 60

It is apparent that as the cutting-edge of one knife strikes the lumber the strain will be borne in the first place by the portion *a* of the head between the knife-sockets; and, in all the forms of heads with which I am acquainted, this portion was of necessity made heavy enough to carry all the strain; whereas by my construction the fastening device of the next following knife is made to act as a brace to sustain the portion *a* by transmitting the strain to the next following portion *a*, which in turn is braced by the fastening device following it, and so on throughout the series until at last a portion of the strain is actually transmitted to the fastening device 75 of the knife then in contact with the lumber, thereby helping to hold the knife solidly and preventing all vibration. It will thus be seen that I am enabled to make the portion *a* of a minimum thickness, which enables me to 80 place more knives around the periphery of the head than if the portions *a* were compelled to be of a thickness suitable to bear all the strain unaided, as in the usual forms of heads.

Moreover, by this construction, being enabled to place the knives closer on the periphery of the head, a greater number of cuts is made per revolution of head than in the old forms, whereby I am enabled either to feed the lumber through the machine at a faster rate for 85 the same number of revolutions of the head, or to run the head at a slower speed for the same rate of feed of the material. Again, the portions *a* being made smaller than in the old form of head, a cutter-head of my construction is much lighter for the same number of knives, and in consequence I can revolve the head much faster without the centrifugal force bursting the head than where the portions *a* are made heavy, thus permitting the 90 lumber to be fed faster than when the old forms of heads are used. 95 100

As the only part of the knife which need project beyond the head is the cutting-edge,

it is plain that I may hold the knife as close to its extreme edge as I desire. This advantage not only prevents vibration of the knife, but takes all undue strain off the fastenings.

5 It will be seen that as the knives wear at the edge or are ground away in sharpening, they may be pushed out so as always to project the same, until they are almost entirely used up, and only enough remains to permit 10 the clamp-blocks to hold them, when they may be removed and new knives inserted.

In a cutter-head using the form of fastening-device herein described, the bolt 4 is arranged diametrically of the socket, and in 15 order to keep the fastening device from being thrown out by centrifugal force when the head is revolving I make the circular sockets so as to contain more than one hundred and eighty degrees of arc, whereby the centrifugal 20 force merely tends to tighten the fastening device and holds the knife tighter.

As in my construction the knife is not slotted, it is much stronger, easier constructed, and, as before stated, may be almost entirely 25 used up before replacing with a new knife.

Having thus fully described my invention, what I claim as new, and desire to secure by Letters Patent, is—

1. The combination, with a cutter-head 30 having a series of knife-sockets and intervening solid portions, of a series of knives and a series of strain-transmitting securing devices, each of which latter serves to hold a knife in its socket, the securing device abutting against the front surface of its respective knife and against the rear surface of the 35 solid portion of the head forward of that knife.

2. The combination, with a cutter-head

having a series of truncated cylindrical knife-sockets and intervening solid portions, of a 40 series of segmental knives and a series of strain-transmitting securing devices for holding the knives in their respective sockets, each device abutting against the front surface of a knife and against the rear surface of the 45 solid portion of the head forward of that knife, substantially as described and for the purpose set forth.

3. The combination, with a cutter-head 50 having a series of peripherally-arranged truncated knife-sockets and intervening solid portions, of a series of segmental knives and a series of strain-transmitting securing devices arranged diametrically of the knife-sockets, each device abutting against the front surface 55 of a knife and against the rear surface of the solid portion forward of that knife.

4. The combination, with a cutter-head having a series of knife-sockets and intervening solid portions and a series of knives 60 in said sockets, of a series of strain-transmitting securing devices for holding the knives in their respective sockets, each of said devices comprising a bolt provided at one end with a block, which bears against the 65 front surface of one of said knives, and at the other end with a screw-threaded nut, which bears against the rear surface of the solid portion of the head forward of that knife.

In testimony whereof I affix my signature in 70 presence of two witnesses.

HARMEN ERNSBERGER.
